United States Patent

Des. 237,951

Patented Dec. 9, 1975

237,951

ANEMOMETER

R. A. Simerl, 528 Epping Forest Road,
Annapolis, Md. 21401

Filed May 10, 1974, Ser. No. 468,641

Term of patent 14 years

Int. Cl. D10—04

U.S. Cl. D10—96

FIG. 1

FIG. 2

FIG. 3

FIG. 1 is a top, right, front perspective view of an anemometer showing my new design;

FIG. 2 is a front elevational view thereof, the rear and left sides, not shown, are plain and unornamented; and

FIG. 3 is a top plan view thereof.

I claim:

The ornamental design for an anemometer, as shown and described.
